CORNER RACK

Samuel L. Snyder, Mill City, Pa.

Application January 8, 1952, Serial No. 17,964

Term of patent 14 years

(Cl. D33—3)

To all whom it may concern:

Be it known that I, Samuel L. Snyder, a citizen of the United States, residing at Mill City, in the county of Wyoming and State of Pennsylvania, have invented a new, original, and ornamental Design for Corner Rack, of which the following is a specification, reference being had to the accompanying drawing, forming a part hereof.

Fig. 1 is a front elevational view of a corner rack, showing my new design.

Fig. 2 is an end elevational view thereof.

Fig. 3 is a top plan view thereof.

I claim:

The ornamental design for a corner rack, substantially as shown.

SAMUEL L. SNYDER.
